UNITED STATES PATENT OFFICE

FRANK B. BIGELOW, OF DETROIT, MICHIGAN, ASSIGNOR TO BIGELOW-LIPTAK CORPORATION, OF DETROIT, MICHIGAN, A CORPORATION OF MICHIGAN

FURNACE WALL

Application filed October 7, 1929. Serial No. 397,809.

My present invention relates to the refractory walls of furnaces and aims to better their construction as well as improve their functioning properties.

5 The invention pertains more particularly to what are known as suspended walls wherein the members comprising the wall or furnace lining are supported independently of one another, or in small groups, on a suitable 10 metal framework, so that the refractory members are not subjected in any material degree to the weight of other members imposed thereon.

One object of the invention is to provide 15 a construction of this type which can be repaired at a minimum of expense, in that only the inner surface bricks or blocks are subject to possible heat injury or damage during ordinary service, and, in the new 20 structure, any one or more of these can be easily replaced without removing or disturbing the outer surface or supporting blocks.

A further aim of the invention is to support 25 a structure wherein the breaking or offsetting of joints between the refractory elements can be readily effected, which is sometimes desirable, when pressure is carried in the circulating air lines and there is tendency 30 for the air to be forced through any cracks, crevices or openings in the furnace lining.

An added salient feature of the invention is that its use permits the employment of a 35 variety of types of refractories in the furnace wall or lining and the proper insulation of the same.

The manner in which the above and other desirable aims are attained will be comprehended by those skilled in the art from an 40 understanding of the present preferred embodiment of the invention, illustrated in detail in the accompanying drawings and described below, like reference numerals being used in the views of the drawings to 45 denote the same parts.

In these drawings both views are fragmentary perspective presentations of small sections of the novel and improved wall.

By reference to such drawings, it will be 50 observed that the metal framework for sup-

porting or sustaining the wall comprises a plurality of spaced, parallel, upright I-beams 11, of which only one is shown, on which are mounted a proper number of vertically-spaced or separated, horizontal bracket-bars 55 12, 12, each of which along its lower part has an inwardly-extended ledge or shelf 13 having a depending flange 14 along its inner edge or margin, whereby the two integral parts 13 and 14 form an elongated hook. 60

Part way up the height of the bracket or bar, it has another, inwardly-projecting, narrower shelf or ledge 15.

Each ledge 15 has resting on and supported by it the outer portions of a row of refractory 65 or heat-insulating bricks or blocks 16 each of which is held securely in position thereon by the flange or hook 14 of the next upper bracket-bar fitting in its top notch 17, the lower corner 18 of each of such blocks being 70 rounded at 19 to permit its introduction into position between adjacent bracket-bars with facility.

Each such brick or block, as is clearly depicted, has a portion 21 designed to fit in under the ledge 13 and behind the flange 14, so that the block is securely maintained in the specified position and relation, the inner face of the block having a projection 22 of less height than the block and having a downwardly, outwardly sloping or inclined, top face 23, the bottom surface of such extension being flush with the corresponding face of the main body of the block and its inner surface 24 parallel to the outer face 25 of the 85 block.

Thus each row of vertically-separated, outer supporting blocks 16 has an inwardly-extended ledge, formed by the projecting parts 22, having a sloping upper surface. 90

A row of inner or lining refractories 26 is supported on each such ledge, each block 26 having a rear projection 27 along its upper portion with a sloping bottom surface 28 companion to, and resting on, the inclined surface 23, each such block 26 having a top, flat, horizontal surface, desirably, but not necessarily, flush or on a level with the upper face of the corresponding ledge 13, the outer vertical face 29 of the section 27 bearing against 95 100

or spaced slightly away from and extending above the complementary face of the outer supporting block 16, the bottom surface of each element 26 being plane and horizontal 5 and its inner surface 32 flat and vertically disposed.

Thus the rows of refractory lining or surface blocks 26 are directly hung on the rows of outer supporting bricks 16, their contacting, cooperating, inclined, surfaces holding them in suitable engagement.

From the illustration, it will be clear that the members 26 do not extend to the bottoms of their sustaining elements 16, and hence 15 there are stepped spaces between the united rows of inner and outer, or surface and supporting, blocks which are occupied by rows of stepped or shouldered filler-bricks 34 of the shape illustrated and which in many instances do not rest on the ledges 13, but are supported solely by the underlying rows of blocks 26.

The filler bricks have shallow spaces or expansion joints between their two-level top 25 surfaces and the under faces of the elements 16 and 26 directly above them and one or both of such gaps, especially the inner one between the parts 34 and 26, may be filled or packed with asbestos or refractory material, 30 as may be best suited to the particular requirements.

Obviously, these filler-blocks 34 lock the companion blocks 26 in place, and to remove any one of the latter, in order to replace it 35 with an undamaged substitute, it is first necessary to take out the filler block directly above it, whereupon the particular block can be lifted sufficiently and detached without disturbing any of the other members, especially the supporting elements 16.

To detach or demount any block 16, the two blocks 34, 34 directly above and below it, as well as the brick 26 in line with it, are taken out, whereupon the member 16 can be tilted 40 sufficiently to allow its removal.

As is illustrated, the upright joints between adjacent supporting or holding blocks 16 are out of register with the joints between the proximate lining or face blocks 26, the vertical joints between the ends of members 34 do 50 not register with those between blocks 26, and the horizontal crevices between refractories 34 and 26 are at a higher level than the spaces between elements 34 and 16.

Hence all of the cracks or fissures are sealed, for all practical purposes, preventing infiltration of air into the furnace or the forcing of the furnace gases out through the wall due to internal gas pressure.

By employing this novel and improved construction and arrangement and cooperation of parts, bricks or blocks of relatively inexpensive type, but yet fully adapted to perform their supporting function, may be used 60 as the sustaining bricks directly mounted on

the metal framework and much more expensive highly-refractory bricks, which are directly exposed to the high heat of the furnace, may be employed for the lining and 70 filler members.

When replacement is required, it is merely necessary to substitute new bricks for the inner or surface ones without demounting or changing the supporting bricks.

Furthermore, in a furnace wall where it is necessary or advisable to use a silicon carbide or other refractory lining, wherein the thermal conductivity is such that it is practically impossible to employ the material in connection with a furnace wall construction having metal supporting members, due to the overheating of the supporting brackets and their resultant deterioration, the new type of wall lends itself for satisfactory employment, because the furnace can be operated under high temperatures without excessive heat losses and without endangering the main, supporting, metallic members, since, in such a case, the silicon carbide or other refractory lining 80 performs its usual function in efficient manner, but the heat which it is capable of transmitting does not reach the metal members by reason of the interposition of the supporting 85 bricks of low heat conductivity.

In addition, a furnace lining may be required of an expensive material which is not such that it can withstand the superimposed weight of a built-up wall construction.

The arrangement shown and described relieves the furnace wall lining of weight and 100 it permits the use of a lower grade and less costly backing or set of supporting bricks.

There are also times when it is prudent or advantageous to replace the entire lining, due to change in fuels or operating conditions and, 105 in the new wall incorporating this invention, this may be quickly and inexpensively accomplished since the inner or service lining itself is easily changed and at much less cost than an entire new wall.

Particular attention is directed to the fact that the inner lining can expand and contract independently of the wall of supporting bricks that the joints of the wall are offset allowing it to be made substantially air-tight, that the 115 outer wall may be sealed tightly and the inner wall may be hung loosely thereon, hence eliminating weight or expansion strains on the individual elements, and that the lining wall may be readily replaced without the expense of renewing the whole wall.

The present invention represents an advantageous and substantial improvement over the structure presented in United States Patent 1,670,490, Jack E. Bigelow, furnace 125 wall construction, granted May 22nd, 1928.

The invention, as defined by the appended claims is susceptible of various embodiments and is consequently not limited to the particular one shown and described.

I claim:

1. In a furnace-wall, the combination of vertically-spaced, horizontal bracket-bars, each with an inwardly-extended, bottom ledge having a depending, marginal flange along its inner edge and a narrower, inwardly-projecting shelf part way up the height of the bar, a row of sustaining-bricks resting on each of said shelves and held thereon by the ledge-flange of the next bar above fitting in aligned recesses of such bricks, each of said bricks having an inwardly-extended projection with a downwardly, outwardly, sloping, top surface, a row of lining bricks supported by each of said rows of sustaining-bricks and having projections with downwardly, outwardly, sloping, bottom surfaces resting on the complementary, upper surfaces of the sustaining-brick projections, the bottom faces of said lining-bricks being above the corresponding faces of said sustaining-bricks, and a row of filler-bricks between said horizontal rows of lining-bricks, each of said filler-bricks having a top, stepped surface to 20 form to the different levels of the bottom faces of said lining and sustaining bricks, the vertical joints between said sustaining-bricks being out of register with the vertical joints between said lining-bricks which they support, the vertical joints between said filler-bricks being out of register with the joints between said lining-bricks.

2. In a furnace-wall, the combination of vertically-spaced, horizontal bracket-bars, each with an inwardly-extended, bottom ledge having a depending, marginal flange along its inner edge and a narrower, inwardly-projecting shelf part way up the height of the bar, a row of sustaining-bricks resting on each of said shelves and held thereon by the ledge flange of the next bar above fitting in aligned recesses of such bricks, each of said bricks having an inwardly-extended projection, a row of lining-bricks supported by each of said rows of sustaining bricks and having projections resting on the complementary sustaining-brick projections, and rows of filler-bricks between said horizontal rows of lining bricks, the vertical joints between said sustaining-bricks being out of register with the vertical joints between said lining-bricks which they support, the vertical joints between said filler-bricks being out of register with the joints between said lining-bricks.

3. In a furnace-wall, the combination of vertically-spaced, horizontal bracket-bars, each with an inwardly-extended, bottom ledge having a depending, marginal flange along its inner edge and a narrower, inwardly-projecting shelf part way up the height of the bar, a row of sustaining bricks resting on each of said shelves and held thereon by the ledge flange of the next bar above fitting in aligned-recesses of such bricks, each of

said bricks having an inwardly-extended projection, a row of lining-bricks supported by each of said rows of sustaining bricks and having projections resting on the complementary sustaining-brick projections, and rows of filler-bricks between said horizontal rows of lining-bricks.

4. In a furnace-wall construction, the combination of a sustaining metal framework, supporting members mounted on and supported solely by said framework in horizontal rows and individually removable from said framework, said members having inwardly-extended horizontally-aligned projections of less height than said members, horizontal rows of inner refractory lining elements having outwardly-extended horizontally-aligned projections supported on and interlocked with said projections of said members, said elements by said co-operating projections being demountably supported solely by and individually on said supporting members, and intermediate refractory filler-blocks between said rows of inner elements and when in place locking said lining elements against detachment from the wall and when removed permitting such detachment.

In witness whereof I have hereunto set my hand.
